UNITED STATES PATENT OFFICE.

WILLIAM H. SAART, OF ATTLEBORO, MASSACHUSETTS, ASSIGNOR TO THE W. H. SAART COMPANY, A CORPORATION OF MASSACHUSETTS.

DESIGN FOR A COIN-HOLDER.

45,356.

Specification for Design.

Patented Mar. 3, 1914.

Application filed January 8, 1914. Serial No. 811,095. Term of patent 3½ years.

To all whom it may concern:

Be it known that I, WILLIAM H. SAART, a citizen of the United States, residing at Attleboro, in the county of Bristol and State of Massachusetts, have invented a certain new, original, and ornamental Design for a Coin-Holder, of which the following is a specification.

In the accompanying drawing which forms a part of this specification,—the figure is a perspective view of a coin holder showing my design.

I claim:

The ornamental design for a coin holder, as shown.

WILLIAM H. SAART.

Witnesses:

RALPH C. ESTES,
HORATIO E. BELLOWES.
